CARL RECHT, OF NEW YORK, N. Y.

Letters Patent No. 76,812, dated April 14, 1868.

IMPROVEMENT IN STOVE-PIPE ELBOWS.

The Schedule referred to in these Letters Patent and making part of the same.

TO ALL WHOM IT MAY CONCERN:

Be it known that I, CARL RECHT, of the city, county, and State of New York, have invented a new and improved Elbow for Stove-Pipes, and other pipes and tubes; and I do hereby declare the following to be a full, clear, and exact description thereof, enabling those skilled in the art to make and use the same, reference being had to the accompanying drawing, forming part of this specification, in which drawing—

Figure 1 represents a longitudinal central section of this invention.

Figure 2 is a side elevation of the same, when the elbow is brought in a different position from that which it occupies in fig. 1.

Figure 3 is a view of the ring *d* detached.

Similar letters indicate corresponding parts.

This invention relates to an elbow-joint, the two parts or shanks of which are united in such a manner that the elbow can be adjusted to any desired angle.

The invention consists in the arrangement of a separate ring, which overlaps the flanges, formed at the ends of both shanks of the elbow, where said shanks join each other, in such a manner that the operation of making the elbow is materially facilitated, and a strong and durable adjustable elbow is obtained.

A represents an elbow-joint for stove-pipes, or tubes of any other character, which is composed of two parts or shanks, *B C*. Each of these parts is provided with a circular flange, *b* or *c*, at that end where it joins the other part, and the two parts are held together by a ring, *d*, which is made of sheet metal, and laps over both flanges *b* *c*, as clearly shown in fig. 1 of the drawing. By this ring the two parts are firmly united, and, at the same time, the part *C* can be turned and brought to the position shown in fig. 1, or to that shown in fig. 2, or to any position intervening between the two.

I am aware that Letters Patent have been granted to A. K. Tupper, July 19, 1859, (24,834,) in which an adjustable elbow-joint is described which has some resemblance to my invention. He provides one of the parts of the elbow with a plain flange, made to overlap the first flange, and serving to hold the two parts of the elbow together. This double flange, however, is exceedingly difficult to make. The metal has to be stretched at certain points to such an extent that it is liable to crack, and the elbow becomes weak and liable to get out of order in a short time.

By using a detached ring, as shown in my drawing, the flanges *b* *c* can be easily made, and the ring itself can be provided at a trifling cost, and without impairing the strength of the metal, so that a strong and durable elbow is obtained.

Although I have only heretofore illustrated my invention by means of a stove-pipe elbow-joint, yet it is likewise applicable to all kinds of pipes and tubes, as, for example, to leaders and conductors of water-pipes, whose elbow-joints, by means of my invention, can be turned and adjusted to any desired angle.

Among the advantages of my invention is the following: That I am enabled to make the parts which compose an elbow for stove, or other pipe or tube, the same metal as the rest of the pipe or tube, without regard to its character for hardness or stiffness, since it is only necessary to produce thereon the flanges or turned-up edges, which are enclosed by the ring *d*. The said ring can be made of any kind of metal, but I prefer to use tough sheet metal for the purpose.

My invention is also applicable to elbows made of cast metal, where flanges *b* *c* are cast thereon in making. I disclaim everything shown and described in the patent of A. K. Tupper, dated July 19, 1859, but

What I claim as new, and desire to secure by Letters Patent, is—

The detached ring *d*, in combination with the plain flanges *b* *c* on the parts *B C* of an elbow, substantially as and for the purpose described.
